UNITED STATES PATENT OFFICE.

ALFRED E. WITTIG, OF ROCHESTER, NEW YORK.

OPERATING MECHANISM FOR SIGNALS AND OTHER DEVICES.

1,390,662.

Specification of Letters Patent. Patented Sept. 13, 1921.

Application filed August 15, 1919. Serial No. 317,721.

To all whom it may concern:

Be it known that I, ALFRED E. WITTIG, a citizen of the State of Bavaria, and resident of Rochester, in the county of Monroe and State of New York, have invented certain new and useful Improvements in Operating Mechanism for Signals and Other Devices, of which the following is a specification.

The present invention relates to operating mechanisms for signals and other devices, an object of the invention being to provide a controlling valve by which a signal member or other device may be shifted in both directions by the suction created in the cylinders of a gas or explosive engine. A further object of the invention is to provide a controlling valve which may be also utilized as an auxiliary air supply valve for the explosive engine.

To these and other ends, the invention consists of certain parts and combinations of parts, all of which will be hereinafter described, the novel features being pointed out in the appended claims.

In the drawings:

Figure 1 shows diagrammatically two signals and their connections with the intake manifold of a gas engine, one of the signals being extended while the other is in non-signaling position;

Fig. 2 is an enlarged top view of the controlling valve;

Fig. 3 is a detail view of the under side of the controlling valve;

Fig. 4 is a fragmentary sectional view showing the manner in which air is admitted to one side of a cylinder as a suction is created in the opposite side;

Fig. 5 is a sectional view through the controlling valve showing the valve in position to connect the intake manifold with one of the cylinders;

Fig. 6 is a detail view of the movable cone member of the valve;

Fig. 7 is a fragmentary sectional view showing the position of the valve when adjusted for supplying air to the intake manifold;

Fig. 8 is an enlarged view of the signal in side elevation; and

Fig. 9 is a fragmentary top view of the signal member showing the latter partially collapsed.

Referring more particularly to the drawings, 1 indicates a part of the vehicle such for instance as the dash. To this part, two

fluid operated devices are secured, each of these fluid operated devices in this instance comprising a cylinder 2 with a piston 3 operating therein to project or retract the signal, which is connected to the piston rod 4.

The signal or device to be operated in this instance comprises a head 5 at the outer end of the rod and a collapsible part consisting of a plurality of sections 6 hinged together at 7 and provided with slots 8 through which the rod 4 is passed. The inner section of the collapsible signal is rigidly secured at 9 to the adjacent end of the piston 3 while the outer section 6 is pivotally connected at 10 to the head 5. This signal is especially adapted for use in connection with a piston rod which must enter a cylinder as the signal collapses during the retraction of the rod. While the particular collapsible form herein shown is desirable, it is apparent that the invention is not limited to this construction.

For operating the signals it is preferred to connect the cylinders with the manifold 11 of an internal explosive engine of which only a fragment is shown. A pipe 12 leads from this manifold to a valve A and from this valve 4 pipes 13, 14, 15 and 16 lead to the opposite ends of the two cylinders 2 for the purpose of creating a suction at any end of either of the cylinders and admitting air to the opposite end so that the movement of the piston 3 in the cylinder may be effected.

This valve, in this instance, comprises a cone shaped casing 17 with which the pipe 12 connects by a port 18, said casing having, in addition, four equi-distantly arranged ports 19 with which the pipes 13, 14, 15 and 16 connect. Operating in the casing 17 is a cone shaped valve 20 provided with a central port 21 having a lateral extension 22, the central port communicating with the port 18 and the lateral port being adapted to be brought into register with any one of the ports 19 in order to connect the pipe 12 with any one of the pipes 16. The valve member 20 also has two diametrically arranged ports 23 which, when the port 22 connects with one of the ports 19, also connects with two of the ports 19, as shown in Fig. 4, for the purpose of admitting air to that end of the cylinder opposite that in which the suction is created in order to facilitate the movement of the piston. This cone valve may be held to its seat by a ring 24 fastened

by screws 25 and a handle 26 on the valve member 20 may be employed for turning the same to its different positions.

A further feature of this invention is the utilization of this valve for supplying auxiliary air to the manifold so as to produce a proper mixture under certain conditions. This is effected in this instance by providing the casing 17 with an opening 27 (see Fig. 7) and turning the valve member 20 until the port 22 therein is brought to register with the port 27. In this position, air will pass into the manifold by way of the port 27 and the pipe 12.

In the operation of this invention when it is desired to project the left hand signal the valve member 20 is turned to connect the pipes 12 and 13 and admit air from the atmosphere to the pipe 14. The retraction of this signal is effected by connecting the pipe 12 with the pipe 14 and the pipe 13 with the atmosphere. Projection of the right hand signal is effected by connecting the pipe 12 with the pipe 16 and the pipe 15 with the atmosphere. Refraction of the right hand signal is effected by connecting the pipe 15 with the pipe 12 and the pipe 16 with the atmosphere. Auxiliary air is supplied to the engine by turning the valve member 20 to connect with the port 27.

From the foregoing it will be seen that there has been provided an operating mechanism for signals or other devices which employs a cylinder with a piston operating therein connected to the signal or device to be operated. This cylinder is adapted to be connected at either end with the intake of a gas engine by a valve, one end of the cylinder being open to the atmosphere while the opposite end is connected with the in-

take manifold. This valve in addition to controlling the admission of air and the suction to either end of the cylinder also provides for an auxiliary air supply to the engine.

What I claim as my invention and desire to secure by Letters Patent is:

1. In combination with a gas engine, a cylinder, a piston operating in the cylinder a device to be operated connected with said piston, a pipe having connection with the intake of the gas engine, two pipes connected with the opposite ends of the cylinder, and a valve arranged to connect either of the last mentioned pipes with the first named pipe and the other of said pipes with the atmosphere.

2. In combination with a gas engine, two cylinders and devices to be operated connected with said pistons, pistons operating in the cylinders, a pipe having connection with the intake manifold of the gas engine, four pipes, two connecting with the opposite ends of each cylinder, and a valve for connecting the first mentioned piping with any one of said four pipes and connecting the pipe of the same cylinder with the atmosphere without effecting the operation of the piston in the other cylinder.

3. In combination with a gas engine, a cylinder a device to be operated connected with said piston, a piston operating in the cylinder, a piping connecting with the intake of the gas engine, and a valve for connecting said piping with the cylinder, said valve being movable to a position to admit air to the piping leading to the intake manifold for the purpose of supplying auxiliary air to the gas engine.

ALFRED E. WITTIG.

It is hereby certified that in Letters Patent No. 1,390,662, granted September 13, 1921, upon the application of Alfred E. Wittig, of Rochester, New York, for an improvement in "Operating Mechanism for Signals and other Devices," errors appear in the printed specification requiring correction as follows: Page 2, lines 59 and 60, claim 2, strike out the words "and devices to be operated connected with said pistons" and insert the same to follow the word "cylinders," line 61; same page, lines 71 and 72, claim 3, strike out the words "a device to be operated connected with said piston" and insert the same to follow the word "cylinder," line 73; and that the said Letters Patent should be read with these corrections therein that the same may conform to the record of the case in the Patent Office.

Signed and sealed this 15th day of November, A. D., 1921.

[SEAL.]

KARL FENNING,
Acting Commissioner of Patents.
